(57) **CLAIM**

The ornamental design for a swim platform for a boat, as shown and described.

DESCRIPTION

FIG. 1 is a perspective view of the swim platform.
FIG. 2 is a rear elevational view of the swim platform.
FIG. 3 is a front elevational view of the swim platform.
FIG. 4 is a right side elevational view of the swim platform, taken from the port side.
FIG. 5 is a left side elevational view of the swim platform, taken from the starboard side.
FIG. 6 is a top view of the swim platform.
FIG. 7 is a bottom view of the swim platform; and,
FIG. 8 is a perspective view of a boat with the swim platform installed on the transom of the boat.
The broken lines shown are included for the purpose of illustrating the unclaimed portions of the article and form no part of the claimed design.
